COPYHOLDER

Sam D. Mathews and James R. Brandt, Houston,
Tex.; said Brandt assignor to said Mathews

Application November 22, 1940, Serial No. 366,652

10 Claims. (Cl. 120—32)

This invention relates to a copyholder for typewriting machines and more particularly to a device of the type which is automatically operable to indicate on a copy the point of copying by the typist.

An object of the invention is to provide a copyholder and position indicator which is automatic in its operation to indicate at all times the point of copying by the typist.

Another object is to provide a device of the class described which is simple in construction, is easy to operate and is accurate in its indication of the position of copying.

Still another object is to provide a device which may be readily placed in or removed from operating position.

Another object is to provide a device which is readily adjustable for different spacings on a copy.

Still another object is to provide a copy holder having a novel driving device which includes a clutching mechanism which is easily engageable or releasable by the typist.

A further object is to provide a copy holder which is driven by a ratchet mechanism operated by a moving element on the typing machine when such machine is restored to position to initiate the typing of a new line.

The foregoing are primary objects and will, together with other objects, be more fully apparent when considered with the following description taken in connection with the accompanying drawings in which:

Fig. 1 is a front elevation of the device embodying the invention;

Fig. 2 is a side elevation of the device shown in Fig. 1;

Fig. 3 is a plan view of the device as shown in operative relation with a typewriter with which such device may be used;

Fig. 4 is a plan view of the holder actuating mechanism with cover removed;

Fig. 5 is a side elevational view taken on line 5—5 in Fig. 4.

Fig. 6 is a sectional view taken on line 6—6 in Fig. 4, the section through the clutch mechanism being on the line 6—6 in Fig. 7;

Fig. 7 is a transverse sectional view through the clutch housing;

Fig. 8 is a transverse sectional view taken on line 8—8 in Fig. 7;

Fig. 9 shows a modified form of the holder actuating mechanism;

Fig. 10 is a sectional view taken on line 10—10 in Fig. 9;

Fig. 11 is a sectional view taken on line 11—11 in Fig. 1.

In Figs. 1, 2 and 3 of the drawings the device of the invention is shown generally, Fig. 3 showing the device as applied to a typewriter 1 having a key board 2 and a traveling carriage 3. Rearwardly of the typewriter 1 is a copyholder 10 having a pointer 11 operatively connected through a cable 12 to an actuating arm 13 which is releasably and adjustably attached to the carriage 3 by means of a clamp 5. The copy carrier 15 of the copyholder is movable vertically by means of a control cable 16 which is attached to a control mechanism generally referred to as 35.

The copyholder comprises a base 14 to which is attached a pair of pillars or columns 17 (Fig. 11) between which is secured a steady plate 18. The copy carrier 15 is recurved at 20 at its opposite edges so that the carrier is slidably longitudinally of the pillars 17. Bearing members 21 may, if desired, be interposed between the recurved edges 20 and the pillars 17.

As already explained the desired movement of the copy carrier 15 is effected by the cable 16 which passes beneath a pulley 22 in the base 14 thence over a sheave 23 mounted on the steady plate 18. The end of the cable 16 is then attached to a lug 24 on the rear side of the copy carrier 15 and adjacent its lower end.

A holding rod 25 is mounted upon the upper end of the copy carrier 15 and is spring pressed toward the carrier so that the friction sleeves 26 bear against the copy and releasably hold such copy in place.

The line which is being copied is indicated by the graduated scales 27 and 28 between which is a slot 29 into which a lug on the pointer 11 extends for attachment to the cable 12 which passes downwardly within side frame members 30 and beneath small pulleys mounted therein so that the closed cable and pointer assembly may be actuated in the manner already described. The side frame members 30 are attached at their lower ends to a rod 31 which is pivotally mounted upon the base 14 so that the frame may swing toward and from the copy carrier 15. This frame is constantly urged toward the carrier by means of tension springs 32 which are attached to the pillars 17 and pins 33 attached to the frame above the pivot point. By means of this construction the scales 27 and 28 engage the copy with sufficient force to hold the copy flat upon the carrier 15 and hence closely contiguous to the characters being copied.

The control mechanism 35 for controlling the movements of the cable 16 is provided with a cover 36 and is mounted upon a base plate 37 secured to the base 14 at one side of the copyholder just described. As shown in Figs. 4 to 8 inclusive, the cable 16 passes beneath a sheave 38 mounted on the plate 37 and thence passes over a drum or reel 39 mounted upon a composite clutch shaft 40 which is journaled in spaced journaled bearing supports 41 and 42. The clutch shaft 40 is tubular in construction and is made up of parts 43 and 44 which are enlarged at their inner ends at 45 and 46 to form a peripheral groove within which a ratchet wheel 48 is mounted. The enlargements 45 and 46 are secured together by means of screws 49 whereby the clutch shaft is made an integral unit.

Intermediate the screws 49 the enlargement 45 is provided with radial openings 50 through which pass clutch members 51 which are adapted to move outwardly into engagement with the ratchet wheel 48 and effect driving engagement therewith whereby the clutch shaft may be driven when driving effort is imparted to the ratchet wheel.

The reel 39 is attached to the section 44 of the clutch shaft so that the cable 16 is wound thereon when the clutch shaft is driven in a manner to be more fully described.

The clutch shaft 40 is provided with a knob 55 at its outer end so that the shaft may be driven manually if desired. This knob assembly is provided with a central bore 56 which is enlarged at 57 to receive a coil spring 58 engaging the inner end of a knob 59 attached to the reduced end 60 of a plunger within the bore 61 in the clutch shaft. The plunger is tapered at 62 at its inner end so that the clutch members 51 are moved radially outward when the button 59 and the plunger are forced inwardly within the bore 61. It is to be understood that the spring 58 is of sufficient strength that the plunger assembly is normally held outwardly but such spring is incapable of removing the assembly outwardly once such assembly has been forced inwardly to effect engagement of the clutch members 51 with the ratchet wheel 48.

In spaced parallel relation with the clutch shaft 40 is a rock shaft 65 mounted in bearings 66 and 67 attached to the base 37. This rock shaft is normally urged in a counterclockwise direction by means of a spring 68 attached to the base 37 and to a collar 69 attached to the outer end of the shaft. Intermediate the bearings 66 and 67 an arm 70 is attached to the rock shaft and a pawl 71 is pivotally attached to such arm at its outer end. This pawl has its outer end 72 formed to engage the teeth 73 on the ratchet wheel 48. The pawl is constantly urged downwardly toward engaging position by tension spring 73' attached to a collar 74 on the shaft and a pin 75 on the pawl.

The rocking of the shaft 65 is limited by means of a collar 76 adjacent the bearing 66, this collar having an undercut portion 77 which provides downwardly facing surfaces engageable with the bearing 66.

From the foregoing it is apparent that the rock shaft 65 may rotate through a predetermined angle when the device is in operation. During this rocking movement of the shaft the pawl 71 moves to engage the ratchet wheel 48 and effect the desired rotation of the clutch shaft 40. The time at which the pawl 71 will engage the ratchet

wheel is, however, determined by a reclining U-shaped space control arm 80, the lower limb of which has a sliding connection with a lug 81 on the base 37. The upper limb of the control arm 80 is provided with stepped surfaces 82, 83 and 84 which are engageable by the pin 75. The position of the space control arm is determined manually and is fixed by notches 85 which are engageable with a lug 86 on the base 37.

As best seen in Figs. 1, 9 and 10, a sleeve 87 is attached to the rock shaft 65 in any desired position by means of a set screw 88. At the outer end of this sleeve is provided a transverse opening to receive the arm 90 which is secured in place by means of a set screw 91. This arm is adapted to be engaged by the carriage 3 of the typewriter 1 or an equivalent element of any typing machine with which the device is used.

The operation of the device is believed apparent from the foregoing description. By way of summary it will be assumed that the copy carrier 15 is at its lowermost position and it is desired to initiate operation of the device. A copy having been secured in place with the holder 25 and behind the scales 27 and 28, the button 59 is pressed inwardly whereby the ratchet wheel 48 is clutched to the clutch shaft 40. The knob 55 is then manually rotated to bring the copy in desired relation to the scale 27 or the scale 28. A pawl 91 fixed on the base 37 engages one of the teeth on the ratchet wheel and holds the copy carrier in this initial position. The connection between the arm 13 and the cable 12 is then adjusted so that the pointer 11 is desirably positioned relative to the copy.

After a line of the copy has been completed carriage 3 is moved to the right for the succeeding line. During the travel of the carriage the arm 90 is engaged thereby and is likewise moved to the right whereby the pawl 71 engages the ratchet wheel 48 and rotates the clutch shaft 40 an amount which is predetermined by the setting of the space control arm 80. At the same time the pointer 11 has been returned to the beginning of the new line of the copy and successive lines are copied by repetition of this mode of operation.

In the modified form of the control mechanism 35 shown in Figs. 9 and 10 like parts are shown by primed reference characters. In this construction the rock shaft 65' is mounted in a journal 100 on the base 37' and an arm 101 is carried on the inner end of the shaft 65'. This arm carries a pin 102 at its outer end and the upward limit of movement of this pin is determined by an ear 103 attached to the bearing 42'.

The pin 102 is adapted to engage a projection 104 on an arm 105 which surrounds the clutch shaft 40' intermediate the clutch assembly and the bearing 41'. This arm pivotally carries pawl 71' which rides upon the teeth 73' on the ratchet wheel 48'. The reel 39' is properly oriented upon the base 37' and is driven by the shaft 40' through the beveled gears 106 which are respectively attached to the shaft 40' and a stub shaft 107 which is journaled in a bearing 108 mounted on the base 37'.

As already indicated the pawl 71' is in constant engagement with the ratchet wheel 48. In order to limit the rotation imparted to the clutch assembly by the rocking of the rock shaft 65' a stepped control block 80' is slidably attached to the bearing 100 and is provided with stepped surfaces 82' and 83' which are adapted to be engaged by the nether side of the arm 101 and

hence limit the downward movement of such arm. The position of the stepped control block 80' is adjustable by means of a lever 110 pivotally mounted upon the bearing 100 and having a pivoted connection with the arm 80'.

While we have shown a specific embodiment of the invention in the description of the foregoing specification it is intended that the invention shall not be confined to such specific construction as the invention broadly comprehends a novel copyholder and position indicator which is automatic in its operation and functions to accurately indicate at all times the point of copying by the typist.

What is claimed is:

1. In a typewriter copyholder, a base, spaced pillars extending upwardly therefrom, a copyholder plate extending tangentially at one side of said pillars and recurved at its edges to slidably fit about the pillars, a cable attached to said plate to raise the plate on the pillars, and means attached to said cable and including a lever to be rocked to lift the copyholder plate step-by-step to expose the lines of a copy held on the plate.

2. In a typewriter copyholder, a base, spaced pillars extending upwardly therefrom, a copyholder plate slidably mounted upon said pillars, a cable attached to said plate to raise the plate on the pillars, a reel mounted upon said base and upon which said cable is wound, and means including a lever operatively connected to said reel and adapted to be rocked to lift the carrier step-by-step to expose the lines of a copy held on the carrier.

3. In a typewriter copyholder, a base, spaced pillars extending upwardly therefrom, a copyholder plate slidably mounted upon said pillars, a cable attached to said plate to raise the plate on the pillars, a reel mounted upon said base and upon which said cable is wound, and means including a carriage-engaging lever operatively connected to said reel and adapted to be rocked to lift the carrier step-by-step to expose the lines of a copy held on the carrier, said last mentioned means including a releasable clutch connection between said lever and said reel.

4. In a copyholder for use with and operable by the movable carriage of a typewriter, the combination including a vertically adjustable copy carrier, driving means for said copy carrier, said means including a ratchet wheel operatively connected to the copy carrier, a rock shaft, a pawl attached to said shaft and adapted to engage said wheel, and a lever mounted on said shaft to be engaged by the movable carriage to rock the shaft and lift the copy carrier.

5. In a copyholder for use with and operable by the movable carriage of a typewriter, the combination including a rock shaft, a lever mounted on said rock shaft and engageable by the type-

writer carriage to rock the shaft, a pawl drivably connected to the rock shaft, a second shaft, a ratchet wheel on said second shaft and engageable by said pawl, a reel, a clutch connection between said ratchet wheel and reel, a copy carrier vertically movable relative to the typewriter, and a control cable on said reel and attached to the carrier to lift the carrier when said lever is rocked.

10 6. In a copyholder for use with and operable by the movable carriage of a typewriter, the combination including a rock shaft, a lever mounted on said rock shaft and engageable by the typewriter carriage to rock the shaft, means on the

15 shaft for limiting the rocking movement thereof, an arm attached to said shaft, a pawl pivoted on said arm, a stepped control arm for adjustably controlling said pawl during initial rocking of the shaft, a second shaft, a ratchet wheel on said second shaft to be engaged and rotated by said pawl, a reel drivably connected to said wheel, a vertically movable copy carrier and a control cable attached to said reel and said carrier.

20 7. In a device of the class described, a tubular shaft, driven means operatively connected to said shaft, a ratchet wheel on said shaft, a plunger movable within said shaft, clutch means movable by said plunger for clutching the ratchet wheel to the shaft, and a pawl reciprocable transversely of the shaft to engage and drive said wheel.

25 8. In a device of the class described, a tubular shaft, driven means operatively connected to said shaft, a ratchet wheel on the shaft, there being radial openings in the shaft interiorly of said ratchet wheel, clutch members in said openings, means movable axially of the shaft for moving said members into clutching engagement with the ratchet wheel, and means for driving said wheel.

30 40 9. In a device of the class described, a shaft, driven means operatively connected thereto, a ratchet wheel releasably mounted on said shaft, a reciprocable pawl mounted to engage and rotate said wheel and shaft, a projection on said pawl, and means engageable by said projection for limiting the movement of the pawl during its engagement with the ratchet wheel.

45 10. In a typewriter copyholder, a base, a frame extending upwardly therefrom, said frame including tubular vertically extending side portions, a copyholder plate in engagement with said side portions at one side of said frame and having its edges contoured to slidably fit upon the side portions, a cable attached to said plate to raise the plate vertically along the frame, and means attached to said cable to move the cable and plate in a step-by-step manner to expose the lines of a copy held on the plate.
